DESIGN FOR A GLASS BOTTLE

Russell G. Twiggs, Pittsburgh, Pa., assignor to J. T. & A. Hamilton Company, a corporation of Pennsylvania

Application October 16, 1934, Serial No. 53,636

Term of patent 7 years

To all whom it may concern:

Be it known that I, Russell G. Twiggs, a citizen of the United States, residing in Pittsburgh, in the county of Allegheny and State of Pennsylvania, have invented a new, original, and ornamental Design for a Glass Bottle, of which the following is a specification, reference being had to the accompanying drawing forming part thereof.

My design relates to the general appearance of the glass bottle, as produced by its conformation and external ornamentation.

In the drawing: Figure I is a front elevation of a glass bottle showing my new design; Figure II is a side elevation of the glass bottle; and Figure III is a rear elevation of the glass bottle.

I claim:

The ornamental design for a glass bottle, substantially as shown and described.

RUSSELL G. TWIGGS.
